CLAIM

The ornamental design for a wireless charger, as shown and described.

DESCRIPTION

FIG. 1 is a perspective view of a wireless charger with a cap in an open state showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view thereof with the cap in a closed and locked state; and,

FIG. 10 is another perspective view thereof with the cap in a closed and released state.

The broken lines depict portions of the wireless charger and form no part of the claimed design.

1 Claim, 10 Drawing Sheets
